(57) **ABSTRACT**

An image forming apparatus includes a cooler and a heater, which includes a heat generation part including resistive heat generators, a first electrode, a second electrode, a first conductor, a second conductor, and a branch channel. The first conductor connects the resistive heat generators and the first electrode. The second conductor extends from the resistive heat generators to a side in a first longitudinal direction of the heater to be connected to the second electrode. The branch channel branches from the second conductor and extends to a side in a second longitudinal direction opposite the first longitudinal direction to be connected to either the second conductor or the second electrode without passing through the first conductor. A cooling ability of the cooler to an end side of the heater in the second longitudinal direction is greater than that to an end side of the heater in the first longitudinal direction.

IMAGE FORMING APPARATUS INCLUDING A COOLER AND A HEATER

CROSS-REFERENCE TO RELATED APPLICATIONS

This patent application is based on and claims priority pursuant to 35 U.S.C. § 119(a) to Japanese Patent Application Nos. 2019-146406, filed on Aug. 8, 2019, and 2020-063726, filed on Mar. 31, 2020, in the Japan Patent Office, the entire disclosure of each of which is hereby incorporated by reference herein.

BACKGROUND

Technical Field

Embodiments of the present disclosure relate to an image forming apparatus.

Related Art

Various types of image forming apparatuses are known, including copiers, printers, facsimile machines, and multi-function machines having two or more of copying, printing, scanning, facsimile, plotter, and other capabilities. Such image forming apparatuses usually form an image on a recording medium according to image data. Specifically, in such image forming apparatuses, for example, a charger uniformly charges a surface of a photoconductor as an image bearer. An optical writer irradiates the surface of the photoconductor thus charged with a light beam to form an electrostatic latent image on the surface of the photoconductor according to the image data. A developing device supplies toner to the electrostatic latent image thus formed to render the electrostatic latent image visible as a toner image. The toner image is then transferred onto a recording medium either directly or indirectly via an intermediate transfer belt. Finally, a fixing device applies heat and pressure to the recording medium bearing the toner image to fix the toner image onto the recording medium. Thus, an image is formed on the recording medium.

The image forming apparatuses often include a heating device. One example of the heating device is the fixing device that fixes toner onto a recording medium under heat. Another example of the heating device is a drying device that dries ink on a recording medium.

SUMMARY

In one embodiment of the present disclosure, a novel image forming apparatus includes a cooler and a heater. The heater includes a heat generation part, a first electrode, a second electrode, a first conductor, a second conductor, and a branch channel. The heat generation part includes a plurality of resistive heat generators. The first conductor is configured to connect the plurality of resistive heat generators and the first electrode. The second conductor is configured to extend from the plurality of resistive heat generators to a side in a first longitudinal direction of the heater to be connected to the second electrode. The branch channel is configured to branch from the second conductor and extend to a side in a second longitudinal direction opposite the first longitudinal direction to be connected to one of the second conductor and the second electrode without passing through the first conductor. A cooling ability of the cooler to an end side of the heater in the second longitudinal direction is

greater than the cooling ability to an end side of the heater in the first longitudinal direction.

BRIEF DESCRIPTION OF THE DRAWINGS

A more complete appreciation of the embodiments and many of the attendant advantages and features thereof can be readily obtained and understood from the following detailed description with reference to the accompanying drawings, 10 wherein:

FIG. 1 is a schematic cross-sectional view of an image forming apparatus according to an embodiment of the present disclosure;

FIG. 2 is a schematic cross-sectional view of a fixing device incorporated in the image forming apparatus;

FIG. 3 is a perspective view of the fixing device;

FIG. 4 is an exploded perspective view of the fixing device;

FIG. 5 is a perspective view of a heating device incorporated in the fixing device;

FIG. 6 is an exploded perspective view of the heating device;

FIG. 7 is a plan view of a heater incorporated in the heating device;

FIG. 8 is an exploded perspective view of the heater;

FIG. 9 is a perspective view of the heater and a connector coupled to the heater;

FIG. 10 is another plan view of the heater;

FIG. 11 is a plan view of a comparative heater, illustrating a general energization path;

FIG. 12 is another plan view of the comparative heater, illustrating an energization path in a case in which an unintended shut occurs;

FIG. 13 is a plan view of the comparative heater with a table indicating the amounts of heat generated by feed lines for each block, in a case in which an unintended shunt occurs;

FIG. 14 is a graph illustrating the total amount of heat generated by the feed lines for each block;

FIG. 15 is a cross-sectional plan view of the image forming apparatus;

FIG. 16 is a cross-sectional side view of the fixing device, illustrating a first example of location of a temperature sensor;

FIG. 17 is another cross-sectional side view of the fixing device, illustrating a second example of location of the temperature sensor;

FIG. 18 is a cross-sectional plan view of the image forming apparatus, illustrating a first example of location of the temperature sensor in a longitudinal direction of the heater;

FIG. 19 is another cross-sectional plan view of the image forming apparatus, illustrating a second example of location 55 of the temperature sensor in the longitudinal direction of the heater;

FIG. 20 is a cross-sectional plan view of an image forming apparatus according to another embodiment of the present disclosure;

FIG. 21 is a plan view of the heater, illustrating a transverse dimension of the heater and a transverse dimension of resistive heat generators incorporated in the heater;

FIG. 22 is a plan view of a variation of the heater;

FIG. 23 is a cross-sectional view of a first variation of the fixing device;

FIG. 24 is a cross-sectional view of a second variation of the fixing device; and

FIG. 25 is a cross-sectional view of a third variation of the fixing device.

The accompanying drawings are intended to depict embodiments of the present disclosure and should not be interpreted to limit the scope thereof. Also, identical or similar reference numerals designate identical or similar components throughout the several views.

DETAILED DESCRIPTION

In describing embodiments illustrated in the drawings, specific terminology is employed for the sake of clarity. However, the disclosure of the present specification is not intended to be limited to the specific terminology so selected and it is to be understood that each specific element includes all technical equivalents that have a similar function, operate in a similar manner, and achieve a similar result.

Although the embodiments are described with technical limitations with reference to the attached drawings, such description is not intended to limit the scope of the disclosure and not all of the components or elements described in the embodiments of the present disclosure are indispensable to the present disclosure.

In a later-described comparative example, embodiment, and exemplary variation, for the sake of simplicity, like reference numerals are given to identical or corresponding constituent elements such as parts and materials having the same functions, and redundant descriptions thereof are omitted unless otherwise required.

As used herein, the singular forms "a," "an," and "the" are intended to include the plural forms as well, unless the context clearly indicates otherwise.

It is to be noted that, in the following description, suffixes Y, M, C, and Bk denote colors of yellow, magenta, cyan, and black, respectively. To simplify the description, these suffixes are omitted unless necessary.

Referring to the drawings, wherein like reference numerals designate identical or corresponding parts throughout the several views, embodiments of the present disclosure are described below.

Initially with reference to FIG. 1, a description is given of an image forming apparatus 100 according to an embodiment of the present disclosure.

FIG. 1 is a schematic cross-sectional view of the image forming apparatus 100.

As illustrated in FIG. 1, the image forming apparatus 100 includes four image forming units 1Y, 1M, 1C, and 1Bk serving as image forming devices, respectively. The image forming units 1Y, 1M, 1C, and 1Bk are removably installed in a body 103 of the image forming apparatus 100. The image forming units 1Y, 1M, 1C, and 1Bk have identical configurations, except that the image forming units 1Y, 1M, 1C, and 1Bk contain developers in different colors, namely, yellow (Y), magenta (M), cyan (C), and black (Bk), respectively. The yellow, magenta, cyan, and black correspond to color-separation components of a color image. Specifically, each of the image forming units 1Y, 1M, 1C, and 1Bk includes a drum-shaped photoconductor 2, a charger 3, a developing device 4, and a cleaner 5. The photoconductor 2 serves as an image bearer that bears an electrostatic latent image and a resultant toner image. The charger 3 charges a circumferential surface of the photoconductor 2. The developing device 4 supplies toner as a developer to the electrostatic latent image formed on the circumferential surface of the photoconductor 2, rendering the electrostatic latent image visible as a toner image. In short, the developing

device 4 forms a toner image on the photoconductor 2. The cleaner 5 cleans the circumferential surface of the photoconductor 2.

The image forming apparatus 100 further includes an exposure device 6, a sheet feeding device 7, a transfer device 8, a fixing device 9, and a sheet ejection device 10. The exposure device 6 exposes the circumferential surface of the photoconductor 2 to form an electrostatic latent image. The sheet feeding device 7 feeds or supplies a sheet P serving as a recording medium. The transfer device 8 transfers the toner image from the photoconductor 2 onto the sheet P. The fixing device 9 fixes the toner image onto the sheet P. The sheet ejection device 10 ejects the sheet P outside the image forming apparatus 100.

The transfer device 8 includes an intermediate transfer belt 11, four primary transfer rollers 12, and a secondary transfer roller 13. The intermediate transfer belt 11 is an endless belt serving as an intermediate transferor entrained around a plurality of rollers. Each of the four primary transfer rollers 12 serves as a primary transferor that transfers the toner image from the corresponding photoconductor 2 onto the intermediate transfer belt 11. The secondary transfer roller 13 serves as a secondary transferor that transfers the toner images from the intermediate transfer belt 11 onto the sheet P. The four primary transfer rollers 12 contact the respective photoconductors 2 via the intermediate transfer belt 11. In other words, each of the photoconductors 2 contacts the intermediate transfer belt 11, thereby forming an area of contact, herein referred to as a primary transfer nip, between each of the photoconductors 2 and the intermediate transfer belt 11. On the other hand, the secondary transfer roller 13 contacts, via the intermediate transfer belt 11, one of the plurality of rollers around which the intermediate transfer belt 11 is entrained. Thus, the secondary transfer roller 13 forms an area of contact, herein referred to as a secondary transfer nip, between the secondary transfer roller 13 and the intermediate transfer belt 11.

Inside the image forming apparatus 100, the sheet P is conveyed from the sheet feeding device 7 along a sheet conveyance passage 14 that is defined by internal components of the image forming apparatus 100. A timing roller pair 15 is disposed between the sheet feeding device 7 and the secondary transfer nip (defined by the secondary transfer roller 13) on the sheet conveyance passage 14.

To provide a fuller understanding of the embodiments of the present disclosure, a description is now given of a series of image forming operations of the image forming apparatus 100 with continued reference to FIG. 1.

When the image forming apparatus 100 receives an instruction to start a print job (i.e., a series of image forming operations), a driver drives and rotates the photoconductor 2 clockwise in FIG. 1 in each of the image forming units 1Y, 1M, 1C, and 1Bk. The charger 3 charges the circumferential surface of the photoconductor 2 uniformly at a high electric potential. According to image information of a document read by a document reading device or print information instructed to print from a terminal, the exposure device 6 exposes the circumferential surface of each of the photoconductors 2 to decrease the electrostatic potential at an exposed portion, thereby forming an electrostatic latent image on the circumferential surface of each of the photoconductors 2. The developing device 4 supplies toner to the electrostatic latent image, rendering the electrostatic latent image visible as a toner image. Thus, the developing device 4 forms a toner image on the photoconductor 2.

The toner image thus formed on the photoconductor 2 reaches the primary transfer nip (defined by the primary

transfer roller 12) as the photoconductor 2 rotates. At the primary transfer nip, the toner image is transferred onto the intermediate transfer belt 11 that is rotated counterclockwise in FIG. 1. Specifically, the toner images are sequentially transferred from the respective photoconductors 2 onto the intermediate transfer belt 11 such that the toner images are superimposed one atop another, as a composite full-color toner image on the intermediate transfer belt 11. The full-color toner image on the intermediate transfer belt 11 is conveyed to the secondary transfer nip (defined by the secondary transfer roller 13) as the intermediate transfer belt 11 rotates. At the secondary transfer nip, the full-color toner image is transferred onto the sheet P supplied and conveyed from the sheet feeding device 7. Specifically, the sheet P supplied from the sheet feeding device 7 is temporarily stopped by the timing roller pair 15. Rotation of the timing roller pair 15 is timed to send out the sheet P to the secondary transfer nip such that the sheet P meets the full-color toner image on the intermediate transfer belt 11 at the secondary transfer nip. Thus, the full-color toner image is transferred onto the sheet P. In other words, the sheet P bears the full-color toner image. Note that after the toner image is transferred from the photoconductor 2 onto the intermediate transfer belt 11, the cleaner 5 removes residual toner from the photoconductor 2. The residual toner herein refers to toner that has failed to be transferred onto the intermediate transfer belt 11 and therefore remains on the surface of the photoconductor 2. The toner image may be a meaningful image such as text or a figure, or a pattern having no meaning per se. The toner image may be a monochrome image.

The sheet P bearing the full-color toner image is conveyed to the fixing device 9, which fixes the full-color toner image onto the sheet P. Thereafter, the sheet ejection device 10 ejects the sheet P outside the image forming apparatus 100. Thus, a series of image forming operations is completed.

Referring now to FIG. 2, a description is given of a configuration of the fixing device 9 incorporated in the image forming apparatus 100 described above.

FIG. 2 is a schematic cross-sectional view of the fixing device 9.

As illustrated in FIG. 2, the fixing device 9 according to the present embodiment includes a heating device 19, a fixing belt 20, and a pressure roller 21. The fixing belt 20 and the heating device 19 disposed inside a loop formed by the fixing belt 20 constitute a belt unit 20U that is detachably coupled to the pressure roller 21. Specifically, the heating device 19 heats the fixing belt 20. The fixing belt 20 is an endless belt serving as a fixing rotator. The pressure roller 21 contacts an outer circumferential surface of the fixing belt 20 to form an area of contact, herein referred to as a fixing nip N, between the fixing belt 20 and the pressure roller 21. Since the pressure roller 21 is disposed opposite the fixing belt 20, the pressure roller 21 serves as an opposed rotator. The heating device 19 includes, e.g., a planar heater 22, a heater holder 23, and a stay 24. The heater holder 23 holds the heater 22. The stay 24 serves as a reinforcement that reinforces the heater holder 23 along a longitudinal direction of the heater holder 23.

The endless fixing belt 20 is constructed of a cylindrical base layer and a release layer. The base layer, made of polyimide (PI), has an outer diameter of 25 mm and a thickness in a range of from 40 μ m to 120 μ m, for example. The release layer, serving as an outermost layer of the fixing belt 20, has a thickness in a range of from 5 μ m to 50 μ m and is made of fluororesin such as tetrafluoroethylene-perfluoroalkylvinylether copolymer or perfluoroalkylvinyl ether

polymer (PFA) or polytetrafluoroethylene (PTFE), to enhance durability of the fixing belt 20 and facilitate separation of toner, which is contained in a toner image on the sheet P, from the fixing belt 20. Optionally, an elastic layer 5 made of, e.g., rubber having a thickness in a range of from 50 μ m to 500 μ m may be interposed between the base layer and the release layer. The base layer of the fixing belt 20 is not limited to polyimide. Alternatively, the base layer of the fixing belt 20 may be made of heat resistant resin such as 10 polyether ether ketone (PEEK), or metal such as nickel (Ni) or steel use stainless (SUS). An inner circumferential surface of the fixing belt 20 may be coated with, e.g., PI or PTFE to produce a slide layer.

The pressure roller 21 has an outer diameter of 25 mm, for example. The pressure roller 21 is constructed of a core 21a, an elastic layer 21b, and a release layer 21c. The core 21a is a solid core made of iron. The elastic layer 21b rests on a circumferential surface of the core 21a. The release layer 21c rests on an outer circumferential surface of the elastic layer 21b. The elastic layer 21b is made of silicone rubber and has a thickness of 3.5 mm, for example. The release layer 21c resting on the outer circumferential surface of the elastic layer 21b is preferably a fluoroplastic layer having a thickness of about 40 μ m, for example, to facilitate separation of the sheet P and a foreign substance from the pressure roller 21.

A spring serving as a biasing member described later causes the fixing belt 20 and the pressure roller 21 to press against each other. Thus, the fixing nip N is formed between 15 the fixing belt 20 and the pressure roller 21. As a driving force is transmitted to the pressure roller 21 from a driver 20 disposed in the body 103 of the image forming apparatus 100, the pressure roller 21 rotates and serves as a driving roller that drives and rotates the fixing belt 20. The fixing belt 20 is thus driven and rotated by the pressure roller 21 as the pressure roller 21 rotates. When the fixing belt 20 rotates, the fixing belt 20 slides on the heater 22. Therefore, in order to facilitate sliding of the fixing belt 20, a lubricant such as 25 oil or grease may be provided between the heater 22 and the fixing belt 20.

The heater 22 is longitudinally disposed along an axial or longitudinal direction of the fixing belt 20. In other words, a longitudinal direction of the heater 22 is parallel to the longitudinal direction (i.e., axial direction) of the fixing belt 20. The heater 22 contacts the inner circumferential surface of the fixing belt 20 at a position opposite the pressure roller 21. The heater 22 is long in a direction perpendicular to a direction in which the sheet P serving as a recording medium passes through the fixing nip N. The heater 22 includes, e.g., 30 a plate-like base 50, a first insulation layer 51 resting on the base 50, a conductor layer 52 including a heat generation unit 60 and resting on the first insulation layer 51, and a second insulation layer 53 that covers the conductor layer 52. In the present embodiment, the base 50, the first insulation layer 51, the conductor layer 52 (including the heat generation unit 60), and the second insulation layer 53 are 35 layered in this order toward the fixing belt 20, in other words, toward the fixing nip N. Heat generated from the heat generation unit 60 is conducted to the fixing belt 20 via the second insulation layer 53.

Unlike the present embodiment, the heat generation unit 60 may be provided on a heater-holder side of the base 50. The heater-holder side of the base 50 is a surface facing the heater holder 23 away from the fixing belt 20. In such a case, 40 since the heat is conducted from the heat generation unit 60 to the fixing belt 20 via the base 50, the base 50 is preferably made of a material having an increased thermal conductivity

such as aluminum nitride. The heater 22 according to the present embodiment may further include an insulation layer on the heater-holder side of the base 50.

The heater 22 may not contact the fixing belt 20 or may contact the fixing belt 20 indirectly via, e.g., a low friction sheet. In the present embodiment, the heater 22 directly contacts the fixing belt 20 to efficiently conduct heat to the fixing belt 20. The heater 22 may contact the outer circumferential surface of the fixing belt 20. However, if the outer circumferential surface of the fixing belt 20 is brought into contact with the heater 22 and damaged, the fixing belt 20 may degrade quality of fixing the toner image on the sheet P. Hence, in the present embodiment, the heater 22 contacts the inner circumferential surface of the fixing belt 20 advantageously.

The heater holder 23 and the stay 24 are disposed opposite the inner circumferential surface of the fixing belt 20. In other words, the heater holder 23 and the stay 24 are disposed inside the loop formed by the fixing belt 20. The stay 24 includes a channel made of metal. Opposed longitudinal end portions of the stay 24 are supported by opposed side walls of the fixing device 9, respectively. The stay 24 supports a stay side of the heater holder 23. The stay side of the heater holder 23 is a surface facing the stay 24 away from the heater 22. Accordingly, the stay 24 retains the heater 22 and the heater holder 23 to be immune from being bent substantially by pressure from the pressure roller 21. Thus, the fixing nip N is formed between the fixing belt 20 and the pressure roller 21.

The heater holder 23 is susceptible to a temperature increase or overheating as the heater holder 23 receives heat from the heater 22. Therefore, the heater holder 23 is preferably made of a heat-resistant material. For example, the heater holder 23 may be made of a heat-resistant resin having a decreased thermal conductivity such as liquid crystal polymer (LCP) or PEEK. In such a case, the heater holder 23 reduces conduction of heat from the heater 22 to the heater holder 23, allowing the heater 22 to efficiently heat the fixing belt 20.

As a print job starts, the heater 22 supplied with power causes the heat generation unit 60 to generate heat, thus heating the fixing belt 20. Meanwhile, the pressure roller 21 is rotated. The rotation of the pressure roller 21 rotates the fixing belt 20. As illustrated in FIG. 2, the sheet P bearing an unfixed toner image is conveyed through the fixing nip N between the pressure roller 21 and the fixing belt 20 that reaches a given target temperature (i.e., fixing temperature). At the fixing nip N, the unfixed toner image is fixed onto the sheet P under heat and pressure.

Referring now to FIGS. 3 and 4, a detailed description is given of the configuration of the fixing device 9.

FIG. 3 is a perspective view of the fixing device 9. FIG. 4 is an exploded perspective view of the fixing device 9.

As illustrated in FIGS. 3 and 4, the fixing device 9 includes a device frame 40, which includes a first device frame 25 and a second device frame 26. The first device frame 25 includes a pair of side walls 28 and a front wall 27. The second device frame 26 includes a rear wall 29. The side walls 28 in pair are disposed on one longitudinal end side (i.e., axial end side) and another longitudinal end side of the fixing belt 20, respectively. The side walls 28 respectively support opposed longitudinal end sides of the heating device 19 and opposed axial end sides of each of the fixing belt 20 and the pressure roller 21. Each of the side walls 28 is provided with a plurality of engaging projections 28a. As the engaging projections 28a engage respective engaging holes

29a penetrating through the rear wall 29, the first device frame 25 is coupled to the second device frame 26.

Each of the side walls 28 has an insertion recess 28b through which, e.g., a rotary shaft of the pressure roller 21 is inserted. The insertion recess 28b is open on a rear wall 29 side and closed on the other side. The closed side defines a contact portion. A bearing 30 is disposed at an end of the contact portion to support the rotary shaft of the pressure roller 21. As opposed axial ends of the rotary shaft of the pressure roller 21 are attached to the respective bearings 30, the pressure roller 21 is rotatably supported by the pair of side walls 28.

A driving force transmission gear 31 serving as a driving force transmitter is disposed on an axial end side of the rotary shaft of the pressure roller 21. In a state in which the pair of side walls 28 supports the pressure roller 21, the driving force transmission gear 31 is exposed outside the side wall 28. Accordingly, when the fixing device 9 is installed in the body 103 of the image forming apparatus 100, the driving force transmission gear 31 is coupled to a gear disposed inside the body 103 to transmit the driving force from the driver. Note that the driving force transmitter that transmits the driving force to the pressure roller 21 may be, e.g., a coupler or pulleys around which a driving force transmission belt is entrained, instead of the driving force transmission gear 31.

Supports 32 in pair (or a pair of supports 32) are disposed at opposed longitudinal ends of the heating device 19, respectively, to support, e.g., the fixing belt 20, the heater holder 23, and the stay 24. Each of the supports 32 includes guide recesses 32a. As the guide recesses 32a move along edges of the insertion recess 28b of the side wall 28, respectively, the support 32 is attached to the side wall 28.

A pair of springs 33 serving as a pair of biasing members 35 is interposed between the pair of supports 32 and the rear wall 29. As the pair of springs 33 biases the stay 24 and the pair of supports 32 toward the pressure roller 21, the fixing belt 20 is pressed against the pressure roller 21 to form the fixing nip N between the fixing belt 20 and the pressure roller 21.

As illustrated in FIG. 4, a hole 29b is provided on one longitudinal end side of the rear wall 29 of the second device frame 26. The hole 29b serves as a positioner, specifically, a fixing-device positioner that positions a body of the fixing device 9 relative to the body 103 of the image forming apparatus 100. On the other hand, the body 103 of the image forming apparatus 100 is provided with a projection 101 serving as a positioner. As the projection 101 is inserted into the hole 29b of the fixing device 9, the projection 101 engages the hole 29b, thus positioning the body of the fixing device 9 relative to the body 103 of the image forming apparatus 100 in the longitudinal direction of the fixing belt 20. Note that no positioner is provided on another longitudinal end side of the rear wall 29 opposite the aforementioned longitudinal end side of the rear wall 29 on which the hole 29b is provided. Such a configuration does not restrict thermal expansion or shrinkage of the body of the fixing device 9 in the longitudinal direction of the fixing belt 20 caused by changes in temperature.

Referring now to FIGS. 5 and 6, a detailed description is given of a configuration of the heating device 19 incorporated in the fixing device 9.

FIG. 5 is a perspective view of the heating device 19. FIG. 6 is an exploded perspective view of the heating device 19. As illustrated in FIGS. 5 and 6, the heater holder 23 includes a rectangular accommodating recess 23a on a belt-side surface of the heater holder 23 to accommodate the

heater 22. Note that the belt-side surface of the heater holder 23 faces the fixing belt 20 and the fixing nip N. The belt-side surface of the heater holder 23 is a surface on a front side in FIGS. 5 and 6. The accommodating recess 23a has substantially the same shape and size as the shape and size of the heater 22. Specifically, however, a length L2 of the accommodating recess 23a in the longitudinal direction of the heater holder 23 is slightly greater than a length L1 of the heater 22 in the longitudinal direction of the heater 22. The accommodating recess 23a is thus slightly longer than the heater 22. Accordingly, even when the heater 22 extends in the longitudinal direction of the heater 22 due to thermal expansion, the heater 22 does not interfere with the accommodating recess 23a. A connector serving as a power supplier sandwiches the heater holder 23 and the heater 22 accommodated in the accommodating recess 23a, thus holding the heater 22. A detailed description of the connector is deferred.

Each of the supports 32 in pair includes a C-shaped belt support 32b, a belt restrictor 32c, and a supporting recess 32d. The belt support 32b is inserted into the loop formed by the fixing belt 20 to support the fixing belt 20. The belt restrictor 32c is a flange that contacts an edge surface of the fixing belt 20 to restrict a longitudinal movement (e.g., skew) of the fixing belt 20. The supporting recess 32d supports the heater holder 23 and the stay 24 with one longitudinal end side of each of the heater holder 23 and the stay 24 inserted into the supporting recess 32d. As the belt support 32b is inserted into the loop formed by the fixing belt 20 on each axial end side of the fixing belt 20, the fixing belt 20 is supported by a free belt system in which the fixing belt 20 is not stretched basically in a circumferential direction of the fixing belt 20, which is a rotation direction of the fixing belt 20, while the fixing belt 20 does not rotate.

As illustrated in FIGS. 5 and 6, a positioning recess 23e serving as a positioner is provided on one longitudinal end side of the heater holder 23. An engagement 32e of the support 32 illustrated on the left side in FIGS. 5 and 6 engages the positioning recess 23e, thus positioning the heater holder 23 relative to the support 32 in the longitudinal direction of the fixing belt 20. By contrast, the support 32 illustrated on the right side in FIGS. 5 and 6 does not include the engagement 32e. Therefore, the heater holder 23 is not positioned relative to the support 32 in the longitudinal direction of the fixing belt 20. The heater holder 23 is thus positioned relative to the support 32 on a single side in the longitudinal direction of the fixing belt 20. Such a configuration does not restrict thermal expansion or shrinkage of the heater holder 23 in the longitudinal direction of the fixing belt 20 caused by changes in temperature.

As illustrated in FIG. 6, a step 24a is provided on each longitudinal end side of the stay 24 to restrict movement of the stay 24 relative to the support 32. Specifically, the step 24a comes into contact with the support 32, thus restricting a longitudinal movement of the stay 24 relative to the support 32. Note that at least one of the steps 24a is arranged relative to the support 32 via a gap. Such an arrangement does not restrict thermal expansion or shrinkage of the stay 24 in the longitudinal direction of the fixing belt 20 caused by changes in temperature.

Referring now to FIGS. 7 and 8, a detailed description is given of a configuration of the heater 22 incorporated in the heating device 19.

FIG. 7 is a plan view of the heater 22. FIG. 8 is an exploded perspective view of the heater 22.

As illustrated in FIG. 8, the heater 22 includes the base 50, the first insulation layer 51 disposed on the base 50, the

conductor layer 52 disposed on the first insulation layer 51, and the second insulation layer 53 that covers the conductor layer 52.

The base 50 is an elongated plate made of metal such as 5 stainless steel (e.g., SUS), iron, or aluminum. The base 50 may be made of ceramic or glass instead of metal. In a case in which the base 50 is made of an insulating material such as ceramic, the first insulation layer 51 sandwiched between the base 50 and the conductor layer 52 may be omitted. 10 Since metal has an enhanced durability against rapid heating and is easy to process, metal is preferably used to reduce manufacturing costs. Among metals, aluminum and copper are preferable because aluminum and copper especially attain an increased thermal conductivity and barely suffer from unevenness in temperature. Stainless steel is advantageous because stainless steel is manufacturable at reduced costs compared to aluminum and copper.

Each of the first insulation layer 51 and the second 20 insulation layer 53 is made of a material having insulating properties such as heat resistant glass. Alternatively, each of the first insulation layer 51 and the second insulation layer 53 may be made of, e.g., ceramic or PI.

The conductor layer 52 includes the heat generation unit 25 60 constructed of a plurality of resistive heat generators 59, a plurality of electrodes 61, and a plurality of feed lines 62 that electrically connects the heat generation unit 60 and the plurality of electrodes 61. Each of the resistive heat generators 59 is electrically connected to any two of the three 30 electrodes 61 in parallel to each other via the plurality of feed lines 62 disposed on the base 50. Thus, the resistive heat generators 59 are electrically connected in parallel to each other.

The resistive heat generators 59 are formed by, for 35 example, coating the base 50 with a paste of silver-palladium (AgPd), glass powder, and the like by screen printing and thereafter firing the coated base 50. Alternatively, the resistive heat generators 59 may be made of a resistive material such as a silver alloy (AgPt) or ruthenium oxide 40 (RuO₂).

The feed lines 62 are conductors having a resistance value 45 smaller than a resistance value of the resistive heat generators 59. The feed lines 62 and the electrodes 61 are made of, e.g., silver (Ag) or AgPd. The feed lines 62 and the electrodes 61 are formed by screen printing of such a material, for example.

Referring now to FIG. 9, a description is given of a connector 70 that is coupled to the heater 22.

FIG. 9 is a perspective view of the heater 22 and the 50 connector 70 coupled to the heater 22.

As illustrated in FIG. 9, the connector 70 includes a housing 71 made of resin and a plurality of contact terminals 72 disposed in the housing 71. Each of the contact terminals 72 is a flat spring and coupled to a harness 73 that supplies 55 power.

As illustrated in FIG. 9, the connector 70 is attached to the heater 22 and the heater holder 23 such that a front side of the connector 70 sandwiches the heater 22 and the heater holder 23 together with a back side of the connector 70. In 60 this state, a contact 72a provided at an end of each of the contact terminals 72 resiliently contacts or presses against the corresponding electrode 61. Accordingly, the heat generation unit 60 is electrically connected to a power supply disposed in the image forming apparatus 100 through the 65 connector 70. This configuration allows the power supply to supply power to the heat generation unit 60. Note that, as illustrated in FIG. 7, at least part of each of the electrodes 61

11

is not coated by the second insulation layer 53 and therefore exposed to secure connection with the connector 70.

Referring now to FIG. 10, a detailed description is given of the heat generation unit 60.

FIG. 10 is another plan view of the heater 22.

As illustrated in FIG. 10, in the present embodiment, the heat generation unit 60 is constructed of a first heat generation group 60A serving as a heat generation part and a second heat generation group 60B serving as another heat generation part. The first heat generation group 60A is a first group of the resistive heat generators 59, which are other than the resistive heat generators 59 on the ends of the plurality of resistive heat generators 59 arranged in a longitudinal direction of the base 50. The second heat generation group 60B is a second group of the resistive heat generators 59, which are arranged on the ends and distinct from the resistive heat generators 59 of the first heat generation group 60A. The first heat generation group 60A and the second heat generation group 60B are separately controllable to generate heat. Specifically, each of the resistive heat generators 59 constructing the first heat generation group 60A (i.e., the resistive heat generators 59 other than the resistive heat generators 59 arranged on the ends) is connected, through a first feed line 62A, to a first electrode 61A provided on a first longitudinal end side of the base 50. Each of the resistive heat generators 59 constructing the first heat generation group 60A is also connected, through a second feed line 62B, to a second electrode 61B provided on a second longitudinal end side of the base 50 opposite the first longitudinal end side of the base 50 on which the first electrode 61A is provided. On the other hand, each of the resistive heat generators 59 constructing the second heat generation group 60B (i.e., the resistive heat generators 59 on the ends) is connected, through a third feed line 62C or a fourth feed line 62D, to a third electrode 61C (different from the first electrode 61A) provided on the first longitudinal end side of the base 50. Like each of the resistive heat generators 59 of the first heat generation group 60A, each of the resistive heat generators 59 arranged on the ends is also connected to the second electrode 61B through the second feed line 62B.

When a voltage is applied to the first electrode 61A and the second electrode 61B, the resistive heat generators 59 other than the resistive heat generators 59 arranged on the ends are energized. Accordingly, the first heat generation group 60A generates heat alone. By contrast, when a voltage is applied to the first electrode 61A and the third electrode 61C, the resistive heat generators 59 arranged on the ends are energized. Accordingly, the second heat generation group 60B generates heat alone. When a voltage is applied to all the first to third electrodes 61A to 61C, the resistive heat generators 59 of both the first heat generation group 60A and the second heat generation group 60B (i.e., all the resistive heat generators 59) generate heat. For example, the first heat generation group 60A generates heat alone to fix a toner image on a sheet P having a relatively small width conveyed, such as a sheet P of A4 size (sheet width: 210 mm) or a smaller sheet P. By contrast, the second heat generation group 60B generates heat together with the first heat generation group 60A to fix a toner image on a sheet P having a relatively large width conveyed, such as a sheet P of A3 size (sheet width: 297 mm) or a larger sheet P. Thus, a heat generation span is determined according to the sheet width.

One approach to further downsize an image forming apparatus and a fixing device is downsizing a heater, which is one of the components disposed inside a loop formed by

12

the fixing device. That is, a fixing belt can be downsized by downsizing the heater in a transverse direction of the heater, that is, a direction indicated by arrow Y and a direction intersecting the longitudinal direction of the heater 22 along the surface of the heater 22 on which the first heat generation group 60A and the second heat generation group 60B are provided in FIG. 10. As a consequence, the fixing device and the image forming apparatus can be downsized. A description is now given of three specific examples of downsizing the heater in the transverse direction of the heater.

A first example is downsizing a heat generation unit (i.e., resistive heat generators) in the transverse direction of the heater. However, the heat generation unit downsized in the transverse direction of the heater narrows a heating span over which the fixing belt is heated, resulting in an increase in temperature peak to maintain the same amount of heat applied to the fixing belt as the amount of heat applied before the heating span is narrowed. An increase in temperature or heating peak may cause the temperature of an overheating detector such as a thermostat or a fuse disposed on a back surface of the heater to exceed a heat resistant temperature. Alternatively, an increase in temperature peak may cause malfunction of the overheating detector. Such an increase in temperature peak also reduces the efficiency of heat conduction from the heater to the fixing belt. Therefore, an increase in temperature peak is unfavorable from the viewpoint of energy efficiency. As described above, downsizing the heat generation unit in the transverse direction of the heater is hardly adopted.

A second example is downsizing, in the transverse direction of the heater, part of the heater without the heat generation unit, electrodes, or feed lines. However, such downsizing may shorten a distance between the heat generation unit and the feed lines or between the electrodes and the feed lines, thus failing to secure the insulation. Considering the structure of the current heater, it is difficult to further shorten the distance between the heat generation unit and the feed lines or between the electrodes and the feed lines.

A third example is downsizing the feed lines in the transverse direction of the heater. The third example has more room for implementation than the first and second examples described above. However, the feed lines shortened in the transverse direction of the heater increases a resistance value of the feed lines. Therefore, an unintended shunt may occur on a conductive path of the heater. In particular, if a resistance value of the heat generation unit is reduced to increase the amount of heat generated by the heat generation unit to speed up the image forming apparatus, the resistance value of the feed lines and the resistance value of the heat generation unit get relatively close to each other. In such a situation, an unintended shunt tends to occur. In order to prevent such an unintended shunt, the feed lines may be upsized in a thickness direction of the heater (i.e., direction intersecting the longitudinal and transverse directions of the heater) while being downsized in the transverse direction of the heater. Such a configuration secures the cross-sectional area of the feed lines prevents an increase in resistance value of the feed lines. However, in such a case, the screen printing of the feed lines is difficult, resulting in a change of the way of forming the feed lines. Therefore, thickening the feed lines is hardly adopted as a solution. In conclusion, in order to downsize the heater in the transverse direction of the heater, the feed lines are downsized in the transverse direction of the heater in anticipation of an increase in resistance value, while a measure is taken against the unintended shunt that may be caused by downsized feed lines.

Referring now to FIGS. 11 to 14, a description is given of the unintended shunt and adverse effects of the unintended shunt, with a comparative heater 122 having a layout identical to a layout of the heater 22 described above as an example.

FIG. 11 is a plan view of the comparative heater 122, illustrating a general energization path. FIG. 12 is another plan view of the comparative heater 122, illustrating an energization path in a case in which an unintended shut occurs.

In the comparative heater 122 illustrated in FIG. 11, when the voltage is applied to the first electrode 61A and the second electrode 61B such that the resistive heat generators 59 of the first heat generation group 60A generates heat alone, the current generally flows through the first feed line 62A, passes through each of the resistive heat generators 59 other than the resistive heat generators 59 arranged on the ends, and then flows through the second feed line 62B.

However, as illustrated in FIG. 12, an unintended diversion of flow occurs when the difference between the resistance values of the feed lines and the heat generation unit is reduced by an increase in resistance value of the feed lines due to the aforementioned downsizing or by a decrease in resistance value of the heat generation unit due to an increase in heat generation amount. Specifically, part of the current passing through the second resistive heat generator 59 from the left in FIG. 12 turns away from the second electrode 61B at a branch X of the second feed line 62B ahead. The shunted current then passes through the resistive heat generator 59 arranged on the left end in FIG. 12 and further passes through the third feed line 62C, the third electrode 61C, the fourth feed line 62D, and the resistive heat generator 59 arranged on the right end in FIG. 12 in this order. Finally, the current joins the second feed line 62B.

Thus, in the comparative heater 122 illustrated in FIG. 12, a branch path E3 is an unintended route portion through which an electric current flows including a part of the second feed line 62B extending from the branch X to the left in FIG. 12, the resistive heat generators 59 arranged on the ends and constructing the second heat generation group 60B, the third electrode 61C, the third feed line 62C, and the fourth feed line 62D.

Such an unintended shunt may occur when the first heat generation group 60A is energized in a configuration in which the conductive path of the comparative heater 122 includes at least a first conductive portion E1 serving as a first conductor, a second conductive portion E2 serving as a second conductor, and the branch path E3 serving as a branch channel. The first conductive portion E1 connects the first heat generation group 60A and the first electrode 61A. The second conductive portion E2 extends from the first heat generation group 60A to a side in a first longitudinal direction S1 (i.e., to the right in FIG. 12) of the comparative heater 122 to be connected to the second electrode 61B. The branch path E3 branches from the second conductive portion E2 and extends to a side in a second longitudinal direction S2 (i.e., to the left in FIG. 12) opposite the first longitudinal direction S1 to be connected to one of the second conductive portion E2 and the second electrode 61B without passing through the first conductive portion E1. In the present embodiment, the second heat generation group 60B and the third electrode 61C are provided on the branch path E3. An unintended shunt may occur even on a conductive path without the second heat generation group 60B or the third electrode 61C, or a conductive path provided with a conductor other than the second heat generation group 60B and the third electrode 61C.

In a case in which an unintended shunt occurs, the current flows through an unexpected path. As a consequence, the temperature distribution of the comparative heater 122 varies due to heat generation of the feed lines 62.

FIG. 13 is a plan view of the comparative heater 122 with a table indicating the amounts of heat generated by the feed lines 62 for each block, in a case in which an unintended shunt occurs.

For example, in the comparative heater 122 illustrated in FIG. 13, the current flows from the first electrode 61A to each of the resistive heat generators 59 of the first heat generation group 60A evenly by 20%. In a case in which the current passing through the second resistive heat generator 59 from the left in FIG. 13 is shunted by 5% at the branch X ahead, the amounts of heat generated by the feed lines 62 for each of first to seventh blocks corresponding to each of the resistive heat generators 59 are as indicated by the table illustrated in FIG. 13.

Since a relatively small amount of heat is generated in a shorter portion of each of the feed lines 62 extending in a transverse direction of the comparative heater 122, the table illustrated in FIG. 13 simply indicates the calculated amounts of heat generated in a longer portion of each of the feed lines 62 extending in the longitudinal direction of the comparative heater 122, excluding the amount of heat generated in the shorter portion. Specifically, calculated is the amount of heat generated in the longer portion of each of the first feed line 62A, the second feed line 62B, and the fourth feed line 62D extending in the longitudinal direction of the comparative heater 122. Since a heat generation amount (W) is represented by the following equation (1), the heat generation amount indicated in the table of FIG. 13 is calculated as the square of a current (I) flowing through each of the feed lines 62 for convenience. Therefore, the numerical values of the heat generation amount indicated in the table of FIG. 13 are merely values calculated simply and may be different from the actual heat generation amount.

$$W=RxI^2 \quad (1)$$

where W represents the heat generation amount, R represents the resistance, and I represents the current.

With continued reference to FIG. 13, a description is given a specific way of calculating the heat generation amount. In the first block, the current flowing through the first feed line 62A is 100% while the current flowing through the fourth feed line 62D is 5%. Therefore, the total amount of heat generated by the feed lines 62 in the first block is 10025, which is the total value of the square of 100 (i.e., 10000) and the square of 5 (i.e., 25). In the second block, the currents flowing through the first feed line 62A, the second feed line 62B, and the fourth feed line 62D are 80%, 5%, and 5%, respectively. Therefore, the total amount of heat generated by the feed lines 62 in the second block is 6450, which is the total value of the square of 80 (i.e., 6400), the square of 5 (i.e., 25), and the square of 5 (i.e., 25). The heat generation amounts are calculated similarly for the other blocks.

FIG. 14 is a graph of the table of FIG. 13, illustrating the total amount of heat generated by the feed lines 62 for each of the first to seventh blocks.

The total heat generation amounts for the first to seventh blocks are asymmetrically illustrated in FIG. 14 with respect to the fourth block located in the center of the heat generation span due to the influence of the unintended shunt.

Such an asymmetrical variation in the heat generation amount of the feed lines 62 causes a longitudinal unevenness in temperature (or unevenness in temperature distribution)

15

of the comparative heater 122. Such a longitudinal unevenness in temperature of the comparative heater 122 causes unevenness in glossiness. Specifically, the glossiness is higher in a higher temperature portion of an image fixed on the sheet P; whereas the glossiness is lower in a lower temperature portion of the image fixed on the sheet P. In short, the entire image exhibits the unevenness in glossiness, leading to a deterioration in image quality. In particular, such unevenness in glossiness is noticeable when the first heat generation group 60A continuously generates heat to fix toner images on a large number of A4 size sheets P conveyed.

To prevent such a longitudinal unevenness in temperature of the comparative heater 122, the following measures are taken in the present embodiment.

FIG. 15 is a cross-sectional plan view of the image forming apparatus 100.

As illustrated in FIG. 15, an airflow generator is disposed in the image forming apparatus 100, as a cooler that cools the fixing device 9. The airflow generator in the present embodiment is an exhaust fan 81 that discharges air out of the body 103 of the image forming apparatus 100. In the present embodiment, intake ports 105 are provided on an upper side wall and a left side wall, respectively, of the body 103 in FIG. 15. An exhaust port 107 is provided on a right side wall of the body 103 in FIG. 15. The exhaust fan 81 is disposed closer to the exhaust port 107 than the fixing device 9 (or the heater 22). When the exhaust fan 81 is driven, the outside air is sucked or taken in through the intake ports 105 and then discharged out through the exhaust port 107. That is, the driven exhaust fan 81 generates an airflow from the intake ports 105 to the exhaust port 107 in the body 103 of the image forming apparatus 100.

In addition, as illustrated in FIG. 15, the device frame 40 of the fixing device 9 includes a plurality of ventilation holes 41. Therefore, the air mainly taken in through the intake port 105 on the upper side in FIG. 15 passes through the ventilation holes 41 of the fixing device 9 and is discharged through the exhaust port 107. Note that the ventilation holes 41 are open for ventilation and different from openings (namely, a sheet entrance and a sheet exit) through which the sheets P are conveyed and the holes into which positioning projections or bolts are inserted to attach the fixing device 9 to the body 103 of the image forming apparatus 100. Further, in the present embodiment, a duct 83 is disposed between the ventilation holes 41 and the exhaust fan 81, as a ventilation channel that guides an airflow from the ventilation holes 41 to the exhaust fan 81.

As the air taken in through the intake ports 105 is susceptible to a heat source of, e.g., the fixing device 9 and increases in temperature while passing through the inside of the body 103 of the image forming apparatus 100. Therefore, in general, the air discharged through the exhaust port 107 is higher in temperature than the air taken in through the intake ports 105. In other words, the air taken in through the intake ports 105 is lower in temperature than the air discharged through the exhaust port 107. In short, a cooling ability with the airflow to a side on which the air is taken in from the outside is greater than the cooling ability to a side on which the air is discharged to the outside.

Therefore, in the present embodiment, to enhance the cooling ability to a higher-temperature side on which the temperature of the heater 22 increases due to the aforementioned unintended shunt, the exhaust fan 81 serving as an airflow generator generates an airflow to the heater 22, from the higher-temperature side on which the temperature is

16

higher (i.e., left side in FIG. 15) to a lower-temperature side on which the temperature is lower (i.e., right side in FIG. 15).

Referring to the direction of the airflow with respect to the comparative heater 122 illustrated in FIG. 12, the airflow is generated in the first longitudinal direction S1 opposite the second longitudinal direction S2 because the temperature increases on an end side (i.e., left side in FIG. 12) of the comparative heater 122 in the second longitudinal direction S2 on which the branch path E3 branches from the second conductive portion E2. That is, the end portion of the comparative heater 122 in the second longitudinal direction S2 illustrated in FIG. 12 (corresponding to a left end portion of the heater 22 in FIG. 15) having a higher temperature is located on an upstream side of the airflow; whereas an end portion of the comparative heater 122 in the first longitudinal direction S1 (corresponding to a right end portion of the heater 22 in FIG. 15) having a lower temperature is located on a downstream side of the airflow. Such a configuration increases the cooling ability to the end side of the heater 22 in the second longitudinal direction S2 (i.e., left side in FIG. 15) on which the temperature is higher than the temperature on the end side of the heater 22 in the first longitudinal direction S1 (i.e., right side in FIG. 15). In other words, a cooling ability of the exhaust fan 81 serving as a cooler to the end side of the heater 22 in the second longitudinal direction S2 is greater than the cooling ability to the end side of the heater 22 in the first longitudinal direction S1.

As described above, the present embodiment enhances the cooling ability to the higher-temperature side on which the temperature of the heater 22 increases due to an unintended shunt, thus preventing the longitudinal unevenness in temperature of the heater 22 and the fixing belt 20.

In order to effectively generate the airflow and enhance the cooling ability, as illustrated in FIG. 15, the exhaust fan 81 is preferably disposed on a side closer to the exhaust port 107 from a center J of a heat generation span H, which is a longitudinal span of the heater 22 over which the heat generation unit 60 including the first heat generation group 60A and the second heat generation group 60B is disposed. In other words, the exhaust fan 81 is preferably disposed on the side in the first longitudinal direction S1 illustrated in FIG. 12 from the center J of the heat generation span H. More preferably, the exhaust fan 81 is disposed on the side closer to the exhaust port 107 from an end portion K1 of the heat generation span H on the side closer to the exhaust port 107. In other words, the exhaust fan 81 is more preferably disposed on the side in the first longitudinal direction S1 illustrated in FIG. 12 from the end portion K1 of the heat generation span H in the first longitudinal direction S1.

In the image forming apparatus 100 having a layout as illustrated in FIG. 15, an axial direction L of the exhaust fan 81 is parallel to a longitudinal direction U (i.e., first longitudinal direction S1 and the second longitudinal direction S2) of the heater 22 or an axial direction V of the pressure roller 21 such that the exhaust fan 81 is disposed on or near an inner surface of the side wall provided with the exhaust port 107 to facilitate discharging of air through the exhaust port 107.

In a case in which the exhaust fan 81 is hardly disposed such that the axial direction L of the exhaust fan 81 is parallel to the longitudinal direction U of the heater 22 or the axial direction V of the pressure roller 21 due to layout reasons, the axial direction L of the exhaust fan 81 may be inclined at an angle of $\pm 0^\circ$ with respect to the longitudinal direction U of the heater 22 or the axial direction V of the pressure roller 21. However, if the inclination angle θ of the

exhaust fan 81 is too large, the exhaust fan 81 might have difficulties in discharging the air through the exhaust port 107. To address such a situation, the inclination angle θ of the exhaust fan 81 is preferably within a range of $\pm 60^\circ$ (i.e., $-60^\circ \leq \theta \leq +60^\circ$) with respect to the longitudinal direction U of the heater 22 or the axial direction V of the pressure roller 21. More preferably, the inclination angle θ of the exhaust fan 81 is within a range of $\pm 45^\circ$ (i.e., $-45^\circ \leq \theta \leq +45^\circ$) with respect to the longitudinal direction U of the heater 22 or the axial direction V of the pressure roller 21, and even more preferably within a range of $\pm 30^\circ$ (i.e., $-30^\circ \leq \theta \leq +30^\circ$) with respect to the longitudinal direction U of the heater 22 or the axial direction V of the pressure roller 21.

Further, as illustrated in FIG. 15, in the present embodiment, a space in which the exhaust fan 81 is disposed is communicated with a space in which a motor 35 is disposed as a drive source of each of the image forming units 1Y, 1M, 1C, and 1Bk. Accordingly, the exhaust fan 81 generates an airflow around the fixing device 9, and also around the motor 35 for each of the image forming units 1Y, 1M, 1C, and 1Bk. As described above, the exhaust fan 81 that cools the fixing device 9 generates an airflow around another object to be cooled such as the motor 35 for each of the image forming units 1Y, 1M, 1C, and 1Bk, a power supply board, the developing device 4, or the exposure device 6. Accordingly, a dedicated exhaust fan is excludable for each object to be cooled. Thus, the image forming apparatus 100 is downsized and manufactured at reduced costs.

As illustrated in FIG. 15, the ventilation holes 41 are preferably located on a side closer to the fixing belt 20 to a side closer to the pressure roller 21, in the device frame 40 of the fixing device 9. In other words, the ventilation holes 41 are preferably located closer to the fixing belt 20 than to the pressure roller 21. Such a location effectively generates an airflow on the side closer to the fixing belt 20 on which the temperature is desirably equalized particularly in the longitudinal direction of the heater 22, thus preventing the unevenness in temperature caused by the aforementioned unintended shunt.

FIG. 16 is a cross-sectional side view of the fixing device 9, illustrating a first example of location of a temperature sensor 34.

As illustrated in FIG. 16, the image forming apparatus 100 includes the temperature sensor 34 disposed at a position corresponding to (or opposite) the ventilation hole 41, as a temperature detector that detects a temperature of the fixing belt 20. Such a location of the temperature sensor 34 attains advantages described below. Note that the temperature sensor 34 may be either a non-contact sensor or a contact sensor.

In the fixing device 9, as the sheet P is heated when passing through the fixing nip N, the water contained in the sheet P is released as water vapor. At this time, the water vapor adhering to a temperature detection part 34a of the temperature sensor 34 as water droplets may cause a temperature detection error. To address such a situation, the temperature sensor 34 is disposed opposite the ventilation hole 41 as in the example illustrated in FIG. 16. Such a location of the temperature sensor 34 facilitates generation of an airflow around the temperature sensor 34 and prevents the water droplets from adhering to the temperature detection part 34a. Accordingly, the temperature detection error is less likely to occur. As the water droplets are prevented from adhering to the temperature detection part 34a, the temperature sensor 34 can be disposed at a position at which water droplets are likely to adhere to the temperature sensor 34. Thus, the present embodiment enhances the layout flexibil-

ity. In addition, as the temperature sensor 34, an inexpensive infrared temperature sensor of which the temperature detection accuracy is likely to decrease due to the attachment of water droplets is adoptable to reduce manufacturing costs. Examples of the inexpensive infrared temperature sensor include a non-contact (NC) sensor and a thermopile.

FIG. 17 is another cross-sectional side view of the fixing device 9, illustrating a second example of location of the temperature sensor 34.

Since the water droplets hardly adhere to the temperature sensor 34, the temperature sensor 34 may be disposed at a position above the heater 22 in a gravity direction at which the temperature sensor 34 is susceptible to water vapor as illustrated in FIG. 17. That is, even in a case in which an upper end of the temperature detection part 34a is located above an upper end of the heater 22 in the gravity direction, the temperature sensor 34 detects the temperature of the fixing belt 20 with accuracy provided that the temperature sensor 34 is disposed at a position corresponding to (or opposite) the ventilation hole 41. In other words, the temperature sensor 34 disposed at such a position detects the temperature of the fixing belt 20 on an exit side of the fixing nip N at which the temperature increases. In short, the temperature sensor 34 detects a temperature rise of the fixing belt 20 with an enhanced accuracy.

FIG. 18 is a cross-sectional plan view of the image forming apparatus 100, illustrating a first example of location of the temperature sensor 34 in the longitudinal direction of the heater 22. FIG. 19 is another cross-sectional plan view of the image forming apparatus 100, illustrating a second example of location of the temperature sensor 34 in the longitudinal direction of the heater 22.

The temperature sensor 34 may be disposed on a side corresponding to a first longitudinal end side of the heater 22 as illustrated in FIG. 18. Alternatively, the temperature sensor 34 may be disposed on a side corresponding to a second longitudinal end side of the heater 22 opposite the first longitudinal end side of the heater 22 as illustrated in FIG. 19.

As in the example illustrated in FIG. 18, in a case in which the temperature sensor 34 is disposed on a side corresponding to a left end side in the longitudinal direction of the heater 22 (in other words, the side in the second longitudinal direction S2 illustrated in FIG. 12 from the center J of the heat generation span H), the position of the temperature sensor 34 is relatively close to a high-temperature portion of the heater 22. That is, the temperature sensor 34 easily detects the high-temperature portion of the fixing belt 20 and therefore detects an excessive temperature rise in advance. Accordingly, the safety is enhanced while the melting toner on the sheet P is prevented from adhering to a fixing rotator (in this case, the fixing belt 20) at high temperatures. In other words, the occurrence of so-called high temperature offset is prevented.

On the other hand, as in the example illustrated in FIG. 19, in a case in which the temperature sensor 34 is disposed on a side corresponding to a right end side in the longitudinal direction of the heater 22 (in other words, the side in the first longitudinal direction S1 illustrated in FIG. 12 from the center J of the heat generation span H), the position of the temperature sensor 34 is relatively close to a low-temperature portion of the heater 22. That is, the temperature sensor 34 easily detects the low-temperature portion of the fixing belt 20, thereby preventing the occurrence of so-called low temperature offset in which unmelted toner adheres to the fixing belt 20 because the heat amount is insufficient to melt the toner.

Referring now to FIG. 20, a description is given of another embodiment of the present disclosure. In the present embodiment, an intake fan 82 is disposed instead of the exhaust fan 81.

FIG. 20 is a cross-sectional plan view of an image forming apparatus 100A according to the present embodiment.

As illustrated in FIG. 20, in the present embodiment, the intake fan 82 serving as a cooler (or an airflow generator) is disposed inside the body 103 of the image forming apparatus 100A. Also, in the present embodiment, the intake port 105 is provided in a lower side wall of the body 103 in FIG. 20; whereas the exhaust port 107 is provided in an upper side wall of the body 103 in FIG. 20. The intake fan 82 is disposed closer to the intake port 105 than the fixing device 9 (or the heater 22). As in the embodiment described above, the device frame 40 of the fixing device 9 is provided with the plurality of ventilation holes 41. The duct 83 is disposed between the ventilation holes 41 and the intake fan 82 to guide an airflow from the intake fan 82 to the ventilation holes 41.

In the present embodiment, the intake fan 82 is configured to generate an airflow from the higher-temperature side on which the temperature of the heater 22 is higher (i.e., left side in FIG. 20) to the lower-temperature side on which the temperature of the heater 22 is lower (i.e., right side in FIG. 20). That is, as in the embodiment described above, a left end portion of the heater 22 in FIG. 20 (corresponding to the end portion of the comparative heater 122 in the second longitudinal direction S2 illustrated in FIG. 12) having a higher temperature is located on an upstream side of the airflow; whereas a right end portion of the heater 22 in FIG. 20 (corresponding to the end portion of the comparative heater 122 in the first longitudinal direction S1 illustrated in FIG. 12) having a lower temperature is located on a downstream side of the airflow. As in the embodiment described above, such a configuration of the present embodiment effectively cools the higher-temperature side on which the temperature of the heater 22 increases due to an unintended shunt, thus preventing the longitudinal unevenness in temperature of the heater 22 and the fixing belt 20.

As illustrated in FIG. 20, the intake fan 82 is preferably disposed on a side closer to the intake port 105 from the center J of the heat generation span H. In other words, the intake fan 82 is preferably disposed on the side in the second longitudinal direction S2 illustrated in FIG. 12 from the center J of the heat generation span H. The intake fan 82 disposed at such a position effectively generates an airflow and enhances the cooling ability. More preferably, the intake fan 82 is disposed on the side closer to the intake port 105 from an end portion K2 of the heat generation span H on the side closer to the intake port 105. In other words, the intake fan 82 is more preferably disposed on the side in the second longitudinal direction S2 illustrated in FIG. 12 from the end portion K2 of the heat generation span H in the second longitudinal direction S2.

If the intake fan 82 is too close to the fixing device 9 or an internal frame 110 that supports the image forming units 1Y, 1M, 1C, and 1Bk, the fixing device 9 or the internal frame 110 resists an airflow generated by the intake fan 82, thus hampering an effective airflow generation. In order to effectively generate an airflow, the intake fan 82 is preferably disposed at a position slightly apart from the internal frame 110 or the fixing device 9. In the image forming apparatus 100A having a layout as illustrated in FIG. 20, the intake fan 82 effectively generates an airflow with the axial direction L of the intake fan 82 inclined at an angle of 45°

with respect to the longitudinal direction U of the heater 22 or the axial direction V of the pressure roller 21.

In a case in which the intake fan 82 is hardly disposed such that the axial direction L of the intake fan 82 is inclined at an angle of 45° with respect to the longitudinal direction U of the heater 22 or the axial direction V of the pressure roller 21 due to layout reasons, the axial direction L of the intake fan 82 may be inclined at an angle of 45°±θ° with respect to the longitudinal direction U of the heater 22 or the axial direction V of the pressure roller 21. However, if the angle θ of the intake fan 82 is too large, the intake fan 82 might have difficulties in generating an airflow. To address such a situation, the angle θ is preferably within a range of ±60° (-60°≤θ≤+60°). More preferably, the angle θ is within a range of ±45° (i.e., -45°≤θ≤+45°), and even more preferably within a range of ±30° (i.e., -30°≤θ≤+30°).

Like the embodiment described above, in the present embodiment in which the intake fan 82 is disposed, the temperature sensor 34 disposed corresponding to (or opposite) the ventilation hole 41 (as illustrated in FIG. 16) prevents water droplets from adhering to the temperature sensor 34, and therefore prevents temperature detection errors, enhances the layout flexibility, and reduces manufacturing costs as an inexpensive temperature sensor is adoptable. In the present embodiment, the temperature sensor 34 can be disposed as in the examples illustrated in FIGS. 17 to 19. The advantages attained by the locations of the temperature sensor 34 illustrated in FIGS. 17 to 19 in the present embodiment are substantially the same as the advantages described above, and therefore a redundant description is herein omitted.

In the embodiments described above, the airflow is generated from the higher-temperature side on which the temperature of the heater 22 is higher to the lower-temperature side on which the temperature of the heater 22 is lower, to enhance the cooling ability to the higher-temperature side. Exhaust fans or intake fans may be separately disposed on the higher-temperature side and the lower-temperature side, respectively, such that the air flows faster on the higher-temperature side than the air on the lower-temperature side. The ventilation holes 41 may be larger on the higher-temperature side than the ventilation holes 41 on the lower-temperature side to increase the air volume on the higher-temperature side. A heat sink serving as a heat radiator may contact the heater 22 such that the number of fins of the heat sink is greater on the higher-temperature side than the number of fins of the heat sink on the lower-temperature side. Alternatively, a Peltier element may be disposed on the higher-temperature side to enhance the cooling ability.

As described above, even in a case in which an unintended shunt occurs in the heater 22, the embodiments of the present disclosure enhance the cooling ability of the cooler (e.g., exhaust fan 81, intake fan 82) to the higher-temperature side on which the temperature of the heater 22 increases, thus preventing a longitudinal unevenness in temperature of the heater 22 and the fixing belt 20. Accordingly, the embodiments prevent defects caused by the unevenness in temperature, such as the unevenness in glossiness, thus maintaining the image quality. Prevention of the unevenness in temperature caused by the unintended shunt allows downsizing of the feed lines in a transverse direction of the heater 22 to downsize the heater 22. Further, according to the embodiments of the present disclosure, the resistance value of the heat generation unit 60 can be decreased while the heat generation amount can be increased to cope with the increase in speed. Thus, the embodiments achieve both downsizing and increase in speed.

As described above, the embodiments of the present disclosure prevent the unevenness in temperature caused by downsizing of a heater. Therefore, the embodiments attain a greater advantage when applied to a heater downsized particularly in a transverse direction of the heater.

FIG. 21 is a plan view of the heater 22, illustrating a transverse dimension of the heater 22 and a transverse dimension of the resistive heat generators 59.

Specifically, in FIG. 21, Q represents the transverse dimension of the heater 22 (or the base 50); whereas R represents the transverse dimension of the resistive heat generators 59. Note that the transverse direction of each of the heater 22 and the plurality of resistive heat generators 59 intersects the longitudinal direction of the heater 22 along the surface of the heater 22 on which the first heat generation group 60A is disposed.

In a case in which the embodiments are applied to the heater 22 in which a ratio (R/Q) of the transverse dimension R of the resistive heat generators 59 to the transverse dimension Q of the heater 22 is not less than 25%, a greater advantage can be attained. In a case in which the embodiments are applied to the heater 22 having a ratio (R/Q) of not less than 40% in the transverse dimension, an even greater advantage can be attained. Note that, in the example illustrated in FIG. 21, the base 50 of the heater 22 is a rectangle and therefore the transverse dimension Q of the heater 22 remains unchanged at any longitudinal position of the heater 22. In a case in which the base 50 has an uneven edge and therefore the transverse dimension Q changes depending on the longitudinal position of the heater 22, the transverse dimension Q of the heater 22 is a smallest transverse dimension of the heater 22 within the longitudinal span of the heater 22 over which the resistive heat generators 59 are disposed.

A resistive heat generator having a positive temperature coefficient (PTC) characteristic may be used to prevent the unevenness in temperature caused by the aforementioned unintended shunt. The PTC characteristic is a characteristic in which the resistance value increases as the temperature increases, for example, a heater output decreases under a given voltage. The heat generation unit 60 having the PTC characteristic starts up quickly with an increased output at low temperatures and prevents overheating with a decreased output at high temperatures. For example, with a temperature coefficient of resistance (TCR) of the PTC characteristic in a range of from about 300 ppm/^o C. to about 4,000 ppm/^o C., the heater 22 is manufactured at reduced costs while retaining a sufficient resistance value for the heater 22. The TCR is preferably in a range of from about 500 ppm/^o C. to about 2,000 ppm/^o C.

The TCR can be calculated using the following equation (2). In the equation (2), T0 represents a reference temperature, T1 represents a freely selected temperature, R0 represents a resistance value at the reference temperature T0, and R1 represents a resistance value at the selected temperature T1. For example, in the heater 22 described above with reference to FIG. 7, the TCR is 2,000 ppm/^o C. from the equation (2) when the resistance values between the first electrode 61A and the second electrode 61B are 10Ω (i.e., resistance value R0) and 12Ω (i.e., resistance value R1) at 25° C. (i.e., reference temperature T0) and 125° C. (i.e., selected temperature T1), respectively.

$$TCR = (R1 - R0) / R0 / (T1 - T0) \times 10^6 \quad (2)$$

The heater to which the embodiments of the present disclosure are applied is not limited to the heater 22 includ-

ing block-shaped (or square-shaped) resistive heat generators 59 as illustrated in FIG. 7.

FIG. 22 is a plan view of a heater 22V as a variation of the heater 22.

Alternatively, for example, the embodiments are applicable to the heater 22V including resistive heat generators 59V having a shape in which a straight line is folded back as illustrated in FIG. 22. The embodiments are also applicable to a heater including resistive heat generators having another shape.

In the embodiments described above, a description has been given of an image forming apparatus including either an exhaust fan or an intake fan as a cooler, for example. Alternatively, the image forming apparatus may include both the exhaust fan and the intake fan. Alternatively, the image forming apparatus may include a cooler other than the airflow generator such as an exhaust fan or an intake fan.

The embodiments of the present disclosure are also applicable to fixing devices as illustrated in FIGS. 23 to 25, respectively, other than the fixing device 9 described above. Referring now to FIGS. 23 to 25, a description is given of some variations of the fixing device 9.

Initially with reference to FIG. 23, a description is given of a configuration of a fixing device 9A as a first variation of the fixing device 9.

FIG. 23 is a cross-sectional view of the fixing device 9A.

As illustrated in FIG. 23, the fixing device 9A includes a pressing roller 90 disposed opposite the pressure roller 21 via the fixing belt 20. The heater 22 sandwiches the fixing belt 20 together with the pressing roller 90 to heat the fixing belt 20. On the other hand, a nip formation pad 91 is disposed inside the loop formed by the fixing belt 20 and opposite the pressure roller 21. The stay 24 supports the nip formation pad 91. The nip formation pad 91 sandwiches the fixing belt 20 together with the pressure roller 21 to form the fixing nip N between the fixing belt 20 and the pressure roller 21.

Referring now to FIG. 24, a description is given of a configuration of a fixing device 9B as a second variation of the fixing device 9.

FIG. 24 is a cross-sectional view of the fixing device 9B.

As illustrated in FIG. 24, the fixing device 9B does not include the pressing roller 90 described above with reference to FIG. 23. In order to attain a contact length for which the heater 22 contacts the fixing belt 20 in the circumferential direction of the fixing belt 20, the heater 22 is curved into an arc in cross section conforming to a curvature of the fixing belt 20. The rest of the configuration of the fixing device 9B is substantially the same as the rest of the configuration of the fixing device 9A described above with reference to FIG. 23.

Referring now to FIG. 25, a description is given of a configuration of a fixing device 9C as a third variation of the fixing device 9.

FIG. 25 is a cross-sectional view of the fixing device 9C.

As illustrated in FIG. 25, the fixing device 9C includes a pressure belt 92 in addition to the fixing belt 20. The pressure belt 92 and the pressure roller 21 form a fixing nip N2 serving as a secondary nip separately from a heating nip N1 serving as a primary nip formed between the fixing belt 20 and the pressure roller 21. Specifically, the nip formation pad 91 and a stay 93 are disposed opposite the fixing belt 20 via the pressure roller 21. The pressure belt 92 is rotatably disposed while accommodating the nip formation pad 91 and the stay 93. As a sheet P bearing a toner image is conveyed through the fixing nip N2 formed between the pressure belt 92 and the pressure roller 21, the pressure belt

23

92 and the pressure roller 21 fix the toner image onto the sheet P under heat and pressure. The rest of the configuration of the fixing device 9C is substantially the same as the rest of the configuration of the fixing device 9 described above with reference to FIG. 2.

The image forming apparatus incorporating the fixing device according to an embodiment described above is not limited to a color image forming apparatus as illustrated in FIG. 1. Alternatively, the image forming apparatus may be a monochrome image forming apparatus that forms a monochrome toner image on a recording medium. In addition, the image forming apparatus to which the embodiments of the present disclosure are applied includes, but is not limited to, a printer, a copier, a facsimile machine, or a multifunction peripheral having at least two capabilities of these devices.

In addition to the electrophotographic image forming apparatus incorporating the fixing device as described above, the embodiments of the present disclosure are applicable to an inkjet image forming apparatus including a drying device that dries ink applied to a sheet. The embodiments of the present disclosure are also applicable to a heat press machine including a heat press part that heats and presses a target object, such as a laminator that heats and presses a film as a covering material on a surface of a sheet such as paper or a heat sealer that heats and presses a sealing part of a packaging material. Such an inkjet image forming apparatus and a heat press machine to which an embodiment of the present disclosure is applied prevent the unevenness in temperature caused by an unintended shunt and cope with downsizing and increase in speed.

According to the embodiments described above, the unevenness in temperature of a heater is prevented.

Although the present disclosure makes reference to specific embodiments, it is to be noted that the present disclosure is not limited to the details of the embodiments described above. Thus, various modifications and enhancements are possible in light of the above teachings, without departing from the scope of the present disclosure. It is therefore to be understood that the present disclosure may be practiced otherwise than as specifically described herein. For example, elements and/or features of different embodiments may be combined with each other and/or substituted for each other within the scope of the present disclosure. The number of constituent elements and their locations, shapes, and so forth are not limited to any of the structure for performing the methodology illustrated in the drawings.

What is claimed is:

1. An image forming apparatus comprising:
a cooler; and
a heater including:
a heat generation part including a plurality of resistive heat generators;
a first electrode;
a second electrode;
a first conductor configured to connect the plurality of resistive heat generators and the first electrode;
a second conductor configured to extend from the plurality of resistive heat generators to a side of the heater in a first longitudinal direction of the heater to be connected to the second electrode; and
a branch channel conductor configured to branch from a first portion of the second conductor and extend to a side of the heater in a second longitudinal direction opposite the first longitudinal direction and further extending to the side of the heater in the first longitudinal direction to be connected to the second electrode.

24

tudinal direction to be connected to a second portion of the second conductor without passing through the first conductor;

5 a cooling ability of the cooler to an end side of the heater in the second longitudinal direction being greater than the cooling ability to an end side of the heater in the first longitudinal direction.

2. The image forming apparatus according to claim 1, wherein the branch channel conductor includes:

10 another heat generation part including at least one resistive heat generator distinct from the plurality of resistive heat generators; and
a third electrode.

3. The image forming apparatus according to claim 1, wherein the first conductor and the second conductor are configured to electrically connect the plurality of resistive heat generators of the heat generation part in parallel to each other, and

15 wherein the plurality of resistive heat generators has a positive temperature coefficient (PTC) characteristic.

4. The image forming apparatus according to claim 1, wherein a ratio of a transverse dimension of the plurality of resistive heat generators to a transverse dimension of the heater is not less than 25%, and

20 wherein a transverse direction of each of the heater and the plurality of resistive heat generators intersects the first longitudinal direction and the second longitudinal direction of the heater along a surface of the heater on which the heat generation part is disposed.

5. The image forming apparatus according to claim 1, wherein a ratio of a transverse dimension of the plurality of resistive heat generators to a transverse dimension of the heater is not less than 40%, and

25 wherein a transverse direction of each of the heater and the plurality of resistive heat generators intersects the first longitudinal direction and the second longitudinal direction of the heater along a surface of the heater on which the heat generation part is disposed.

6. The image forming apparatus according to claim 1, wherein the cooler is an airflow generator, and

30 wherein the airflow generator is configured to generate an airflow to the heater in the first longitudinal direction.

7. The image forming apparatus according to claim 6, further comprising:

35 a device frame configured to support the heater, the device frame having a ventilation hole; and
a ventilation channel disposed between the airflow generator and the ventilation hole to guide the airflow.

8. The image forming apparatus according to claim 7, further comprising:

40 an endless belt configured to contact the heater; and
an opposed rotator configured to contact the endless belt to form a fixing nip between the endless belt and the opposed rotator,

45 wherein the ventilation hole is located closer to the endless belt than to the opposed rotator.

9. The image forming apparatus according to claim 6, further comprising a

50 body having an intake port configured to take in air from outside and an exhaust port configured to exhaust the air outside,
wherein the airflow generator is an exhaust fan disposed closer to the exhaust port than the heater, and
55 wherein an axial direction of the exhaust fan is inclined at an angle within a range of $\pm 60^\circ$ with respect to the first longitudinal direction and the second longitudinal direction of the heater.

25

10. The image forming apparatus according to claim 9, wherein the exhaust fan is disposed on the side in the first longitudinal direction from a center of a heat generation span, and
 wherein the heat generation span is a longitudinal span of the heater over which the heat generation part is disposed.
11. The image forming apparatus according to claim 9, wherein the exhaust fan is disposed on the side in the first longitudinal direction from an end portion of a heat generation span in the first longitudinal direction, and wherein the heat generation span is a longitudinal span of the heater over which the heat generation part is disposed.
12. The image forming apparatus according to claim 6, further comprising a body having an intake port configured to take in air from outside and an exhaust port configured to exhaust the air outside,
 wherein the airflow generator is an intake fan disposed closer to the intake port than the heater, and wherein an axial direction of the intake fan is inclined at an angle within a range of 15° to 105° with respect to the first longitudinal direction and the second longitudinal direction of the heater.
13. The image forming apparatus according to claim 12, wherein the intake fan is disposed on the side in the second longitudinal direction from a center of a heat generation span, and
 wherein the heat generation span is a longitudinal span of the heater over which the heat generation part is disposed.
14. The image forming apparatus according to claim 12, wherein the intake fan is disposed on the side in the second longitudinal direction from an end portion of a heat generation span in the second longitudinal direction, and
 wherein the heat generation span is a longitudinal span of the heater over which the heat generation part is disposed.
15. The image forming apparatus according to claim 8, further comprising a temperature detector disposed between the ventilation hole and the endless belt to detect a temperature of the endless belt.
16. The image forming apparatus according to claim 15, wherein the temperature detector is an infrared temperature sensor.

26

17. The image forming apparatus according to claim 15, wherein the temperature detector includes a temperature detection part, and wherein an upper end of the temperature detection part is located above an upper end of the heater in a gravity direction.
18. The image forming apparatus according to claim 15, wherein the temperature detector is disposed to a side in the first longitudinal direction from a center of a heat generation span, and wherein the heat generation span is a longitudinal span of the heater over which the heat generation part is disposed.
19. The image forming apparatus according to claim 15, wherein the temperature detector is disposed to a side in the second longitudinal direction from a center of a heat generation span, and wherein the heat generation span is a longitudinal span of the heater over which the heat generation part is disposed.
20. An image forming apparatus comprising:
 an airflow generator configured to generate an airflow;
 and
 a heater including:
 a heat generation part including a plurality of resistive heat generators;
 a first electrode;
 a second electrode;
 a first conductor configured to connect the plurality of resistive heat generators and the first electrode;
 a second conductor configured to extend from the plurality of resistive heat generators to a side in a first longitudinal direction of the heater to be connected to the second electrode; and
 a branch channel conductor configured to branch from a first portion of the second conductor and extend to a side of the heater in a second longitudinal direction opposite the first longitudinal direction and further extending to the side of the heater in the first longitudinal direction to be connected to a second portion of the second conductor without passing through the first conductor,
 an end portion of the heater in the first longitudinal direction being located on a downstream side of the airflow generated by the airflow generator,
 another end portion of the heater in the second longitudinal direction being located on an upstream side of the airflow generated by the airflow generator.
